UNITED STATES PATENT OFFICE

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA

FIRE EXTINGUISHING SYSTEM

Application filed November 7, 1930. Serial No. 494,141.

This invention relates to improvements in fire extinguishing systems, and more particularly in that type of system employing CO₂ or similar fluid fire extinguishing medium which is normally maintained under high pressure in suitable containers to be released in the event of fire within a prescribed area.

One object of my invention is to provide an efficient assembly including a battery of 10 containers for the CO₂ or other medium, together with means for releasing the contents of said containers under predetermined conditions.

Another object of the invention is to provide an assembly of the stated character in 15 which provision is made for simultaneously releasing the contents of a plurality of the containers through a common actuating mechanism.

Still another object of the invention is to provide an assembly of the stated character in which provision is made for releasing the contents of the containers automatically as a 20 result of predetermined abnormal temperature conditions in a prescribed area.

The invention further resides in certain structural and mechanical features herein-after set forth and illustrated in the attached drawings, in which:

Figure 1 is a side elevational view of an 25 assembly made in accordance with my invention;

Fig. 2 is an end elevational view of the assembly, and

Figs. 3 and 4 are detached perspective 30 views of elements of the apparatus.

With reference to the drawings, the apparatus forming an embodiment of my invention may comprise a plurality of containers 1 35 of a type adapted to hold CO₂ or other fluid fire extinguishing medium under high pressures. In the present instance, the apparatus comprises two banks or parallel rows of said containers, these rows being designated in Fig. 2 by the reference numerals 2 and 3 respectively. The containers are mounted in

the present instance in a suitable supporting framework 4, this framework comprising uprights 5 connected transversely by a plurality 40 of vertical spaced bars 6 and longitudinally

by bars 7. Both the uprights and their connecting bars are made in the present instance of angle iron, and it will be noted that the upper or horizontal flange of the connecting bars 7 overlies the corresponding 45 flange of the lowermost of the transverse bars 6.

Extending longitudinally of the frame and joining the lowermost of the said bars 6 at points intermediate their ends are longitudinal bars 8 arranged to form with the bars 7 seats for the containers 1 of the banks 2 and 3, as clearly illustrated in Fig. 2. In each instance, the vertical flange of the angle bar 8 constitutes a stop for the bottoms 50 of the said containers limiting their movement inwardly of the frame. Bars 9 corresponding to the bars 8 connect the two overlying transverse bars 6 and constitute means for supporting a plurality of pairs of upright bars 11, these bars constituting in effect retainers engaging the rear sides of the containers 1 and tending to support the containers in their relatively spaced relation 55 longitudinally of the supporting bars 7 and 8. Intermediate the containers of the respective parallel banks are retaining bolts 12 which extend from the respective bars 9 outwardly towards the opposite sides of the frame and at their outer ends are adapted 60 to receive clamping elements 13 which through the medium of a nut 14 on the threaded extremities of the bolts 12 are secured firmly against the outer sides of the adjacent containers whereby the latter are 65 held firmly against the vertical bars 11 and are thereby effectively anchored in the frame. The containers are readily released by backing off the nut 14 and removing the clamps 13, and may then be removed from the opposite sides of the frame for refilling and 70 for the purpose of replacing the empty containers with full ones. The aforescribed construction affords a simple relatively inexpensive and highly efficient support for the 75 containers.

Each of the containers 1 is provided at the top with a suitable valve or closure device 16 whereby the compressed fluid contents are retained under normal conditions without 80

leakage and whereby the said contents are released when required by abnormal temperature conditions. A device suitable for this purpose is illustrated in United States Patent No. 1,874,356. The details of this device form no part of the present invention and are not illustrated or described. The devices 16 of the various containers of each series are individually connected through ducts 17 with a manifold 18, which manifolds are mounted in the upper end of the frame 4, one end of each manifold being extended or connected through suitable piping with the particular area in which the apparatus is effective. The manifolds 18 are supported in depending brackets 19, 19 suitably secured to the upper part of the frame 4, and connection between the manifold and the ducts 17 is made through suitable L's 21.

29 The devices 16 are adapted to be actuated to release the contents of the containers to the ducts 17 and the manifold 18 through the medium of an actuating lever 22, and the levers of the devices of the respective series 25 or banks of containers are connected individually through rods 23 with actuating rods 24 which are longitudinally movable in the frame 4. Each of the rods 24 is slidably mounted at one end in a bracket 25 mounted 29 on and secured to one of the upper cross bars 6, while the opposite end is similarly supported in a bracket 26 secured at the opposite end of the frame. Intermediate the ends, the said rods are supported by bearing brackets 27 which as shown in Fig. 2 are suspended from the upper side rails of the frame. The rod 24 slides freely in the bearings in the longitudinal direction, and the arrangement is such that a predetermined movement 45 of the rod effects an actuation through the connecting links 23 and the lever 22 of the release devices 16 whereby the fluid contents of the containers are permitted to flow into the manifold 18.

45 Carried by each of the brackets 26 is a pivoted lever 31, these levers being operatively connected respectively with the rods 24. Also pivotally mounted upon an arm 32 of each of the brackets 26 is an arm 33 which 50 carries a weight 34 and which comprises a projection 35 adapted to engage a shoulder 36 on the lever 31 whereby when the arm 33 is dropped from an elevated position, shown 55 in Fig. 1, by means hereinafter described, the said member 35 engaging the shoulder 36 of the lever 31 drives this lever rearwardly and thereby causes a movement in the direction of the arrow, see Fig. 1, of the rod 24, such movement resulting in an actuation of 60 the release devices 16 as previously described. Under normal conditions, the arm 33 is supported in the elevated position by a stirrup or yoke 37 which engages over one arm 38 of a bell crank lever 39 forming a part 65 of an automatic release device designated

generally by the reference numeral 41. This device may be made in accordance with the principles disclosed in my co-pending application Serial Number 460,511, filed June 11, 1930. Since the details of this release device form no part of the present invention, the details of construction are not illustrated and it is sufficient to state that it is of a type commonly employed in fire-extinguishing apparatus and known in the trade as a release 75 box.

As previously set forth, the release device 41 comprises the bell crank lever 39 one arm of which supports the weighted arm 33, while the other arm engages in a suitable locking means within the device and is maintained thereby until such time as the said release device is actuated as a result, for example, of the effect of an abnormal temperature within the zone protected by the apparatus upon 80 a thermosensitive switch element 40. Such actuation of the release 41 results in a release of the lever 39 and actuation as previously described of the release devices 16 of the containers 1. In order to prevent accidental operation of the device through an unauthorized movement of the lever 31, the arm 33 is provided with a pair of teats 42 and 43 respectively. The latter of these devices, engaged behind an opposed teat 44 on the 85 lower end of the lever 31, prevents elevation of the lever 33 sufficient to permit detachment of the stirrup 37 from the supporting arm 38. The teat 42 by interengagement with the hooked extremity 45 of the arm 33 also 90 acts to prevent displacement of the lever 31 to a sufficient extent to actuate the devices 16. 100

The assembly described above has the advantages of simplicity and compactness of form and is highly efficient in operation. 105

I claim:

In fire-extinguishing apparatus, the combination with a container for a fluid fire-extinguishing medium, of a releasable closure member for said container, a longitudinally 110 slidable actuating rod operatively connected with said releasable closure member, a pivoted lever operatively connected with said rod, actuating means comprising a member adapted when released to impinge upon the said 115 pivoted lever to thereby actuate the said rod and through said rod to release the said closure means, and interlocking means on said pivoted lever and the actuating member for preventing accidental displacement of the 120 said actuating rod.

ARTHUR C. ROWLEY.
